UNITED STATES PATENT OFFICE

FREDERICK CAMPKIN, OF WEST HAVEN, CONNECTICUT, ASSIGNOR TO THE HALL ORGAN COMPANY, OF WEST HAVEN, CONNECTICUT, A CORPORATION OF CONNECTICUT

ORGAN

Application filed June 16, 1930. Serial No. 461,373.

The present invention has relation to pipe organs and consists of improved means for effecting the operation and the control of the stops of the organ. Heretofore the stop keys 5 are usually separately and selectively operated to place the stops in both the on and off positions and in some instances means have been previously proposed whereby the stops are separately and selectively brought into 10 the on position and then collectively returned to the off position.

According to the present invention, the stops are separately brought into the on position by selective operation of the respective 15 stop key and then all the stops set in the on position, are thrown back to the off position by a single operation or touch of anyone of the stop keys. All the stops are so arranged and associated with each other that upon initial or first touch of a stop key the stop 20 associated therewith is brought into the on position. Any number of stops can be brought into the on position and in which position they will remain until any one of the stop 25 keys is operated or brought to a point beyond the position it is in after the first or initial operation. The operation of these stop keys may be termed a double touch action, that is, on the first touch of the key the stop is 30 brought into the on position and then a double or advanced touch of any one of the keys, whether or not this key is in the on position, will effect operation of a control device which will cause operation of the actuating 35 means for the various stops. Each stop has its own actuating mechanism comprising an on and an off magnet operated through a suitable electric circuit and each magnet in turn effects operation of pneumatic actuators which are arranged to open ports to admit compressed air to effect operation of the mechanism which causes the stops to open or close to bring the same respectively into the on or off positions.

45 The mechanism or means for actuating the individual stops is of any suitable kind and there is such a mechanism for each stop. According to the present invention a common control device is provided and designed so 50 that this single control device will operate to

control one or more stops. This device and the means comprising the double touch action associated with the stop keys form essential parts of the present invention. The improved device and means include the usual 55 stop keys, each being connected with a spring actuated cleaver. Each stop key carries a movable contactor which is brought into contact with a fixed contactor when the double or advanced touch is given to the key. This 60 latter contactor completes the electric circuit which effects operation of the off magnet to throw the on stops into the off position. In the first touch of the stop key the contact is not made as above stated; therefore said 65 electric circuit is not completed but in this first touch, either by electrical or mechanical means, the selected stop is brought into the on position.

An embodiment of the invention will be 70 described hereinafter with reference to the accompanying drawings; wherein—

Figure 1 is a sectional view showing the individual stop actuating mechanism together with the control mechanism and the 75 stop actuating means, the latter being shown diagrammatically; and

Figure 2 is a diagram showing the arrangement of the different apparatus or means employed and also the arrangement of 80 the electric circuits.

The salient feature of the present invention is the double touch means or mechanism employed for actuating individual stops and the common associated control device or 85 mechanism forms another part of the invention. Any well known means for operating the stops may be employed and therefore such means are only illustrated diagrammatically in the accompanying drawings.

Referring to the aforesaid drawings the means for actuating the individual stops are similar in construction and arrangement and it will be understood that one of such devices is employed for each stop. Said actuating 95 means comprises the key 1 which is carried by the cleaver 2 pivotally suspended from a part of the organ key-board framework 3. The means for suspending this cleaver includes a hanger 4 and said cleaver is con- 100

nected thereto so as to pivot on the pin 5. A spring 6 is employed to return the key and cleaver to the normal or off position when the operation for returning the said key to the off position has been performed. The spring tension which controls said key and cleaver is adjusted by means of screw 7 engaged within a threaded hole in a part of the key-board framework of the organ.

10 The key 1 on the underside thereof carries an insulated resilient pad 8 and which pad lies over a fixed contactor 9. The key 1 carries the movable contactor 10 which is insulated from said fixed contactor 9 by means of the insulating pad 8. The key-board frame carries a fixed contact 11 which is electrically connected to the feed or source of electric current by conductor 12. The conductor 13 connects the contactor 9 with the magnet 14 of the control device 15. The latter device consists of a casing 16 enclosing the magnet 14 and which casing is sub-divided to provide air chamber 17 and air passage 18. The control device comprises as other 25 working parts, besides the magnet, a movable block 19 which carries the movable contactors 20. The said block 19 is raised by means of the pneumatic actuator device 22 which is inflated by air so as to lift said block 30 19 to bring the movable contactors 20 into contact with the fixed contactors 21 which latter contact completes the circuit through conductor 23 to the off magnet or magnets 24. The latter magnets are located in the dia- 35 grammatic illustration of the operating means 25. As previously explained this operating means or mechanism will be provided with as many on and off magnets as required to correspond with the number of stops of the organ. As previously explained, the on and off magnets are operated in the usual way by the ordinary operation of the respective key 1 which in said operation is not brought to a position beyond that shown in Figure 1 40 45 wherein the contactors 9 and 10 are not in contact.

In the operation of the improved means or device, a stop key 1 is initially operated by the first touch in a manner common to practice, that is, pressure on the key will operate the pivoted cleaver 2 which, through the medium of connecting link 26 operates lever 27 and the latter in turn operates a suitable device for mechanically effecting the operation of the means for placing the stops in the on and off positions. This means operates in the usual way common to other organ stop actuating mechanisms to open the respective port to admit compressed air.

50 In common practice when electrical means are employed the on magnet is retained in the operative position until means are brought into action to de-energize said on magnet and energize the off magnet to throw the stop to its normal or off position. With

the present invention, the action of returning the stops to their normal or closed position is greatly simplified and therewith any combination of stops may be readily brought into action by the first or initial touch of the respective keys. To get various combinations the stop keys may be operated together or separately with the double touch and if the key or keys are held in the operated position, the respective magnets will remain in the on position, but other stop keys then in the on position will be returned to the off position.

55 In the operation of the improved device any number of stops may be placed in the on position and upon operation of any one of the keys with increased pressure or, as hereinbefore termed, a double touch, the movable contactor 10 carried by the operated key 1 is brought into contact with the fixed contactor 9 by compression of the insulating pad 8 which is preferably composed of soft elastic material such, for example, as a felt pad. When the contactor 9 contacts with contactor 10, the circuit through conductor 13 is established and the magnet 14 of the control device 15 is actuated to move the valve stem 28. This valve stem carries the valves 29 and 30. The valve 30 opens the port between the chamber 17 and the air passage 18 and 95 when said valve 30 is open valve 29 closes the outlet port 31 of the aforesaid passage 18. When air is admitted through passage 18 the pneumatic actuator 32 is inflated to raise the block 19 carrying the contactors 20. Contact is made with the contactor plate 22 and through this contact electric circuits are established to operate all the off magnets collectively so as to close all the open stops by the double touch operation of any one of the 100 stop keys, as previously described.

105 The essential feature of the invention hereinbefore described is the so termed double touch mechanism used either alone or conjunctively with a control device electrically connected therewith. Both of said means or devices may be used separately or together with various known means for mechanically or electrically operating the stops of an organ and it is to be understood that any modification, either in the construction or application of the invention hereinbefore described coming fairly within the terms of the appended claims shall be covered thereby.

110 I claim:

115 1. A stop action device for organs comprising a stop, a key arranged to be operated with a double touch, the first or initial touch placing said stop in the on position and the double or advanced touch returning associated stops in the on to the off position.

120 2. A double touch action for organs comprising a stop and a single key selectively 125

operated to place said stop in the on position and associated stops in the off position.

3. A double touch stop action device for organs comprising a key associated with a stop and means whereby upon first touch of said key said stop is placed in the on position and in the double or advanced touch of said key associated stops then in the on position are placed in the off position.

10 4. In an organ a plurality of stops, each stop being operated by an individual key, said key having a double touch action whereby with the initial operation of said key said stop is placed in the on position and in the double or advanced touch of said key said stop is placed in the off position.

5 5. In an organ a plurality of stops, each stop being operated by an individual key, said key having a double touch action whereby with initial operation of said key said stop is placed in the on position, with the double or advanced touch of said key said stop is placed in the off position and means whereby the double touch of one key will effect the 20 operation of changing all stops from the on 25 position into the off position.

6. In an organ a plurality of stops, an operating key for each stop, said key having a double touch action whereby selective operation of one key will place the associated stop in the on position and means comprising a common control device whereby the double or advanced touch of said key will change all 30 stops in the on position to the off position.

35 7. In an organ a plurality of stops, an operating key for each stop, said key having a double touch action whereby selective operation of one key will place the associated stop in the on position, means comprising a common control device whereby the double or advanced touch of said key will change all stops in the on position to the off position and said control device comprising electro-pneumatic means for establishing electric circuits 40 for a plurality of magnets which effect separate operation of said stops.

8. In an organ a plurality of stops, an individual operating key for each stop, said key having a double touch action whereby with the initial operation of a selected key an actuating magnet associated with said stop is energized to place the associated stop in the on position and said key with the double or advanced touch thereof establishing an electric 55 circuit to energize a magnet which effects the operation of placing said stop in the off position.

9. In an organ a plurality of stops, an individual operating key for each stop, said key having a double touch action whereby with the initial operation of a selected key an actuating magnet associated with said stop is energized to place the associated stop in the on position, said key by a double or advanced 60 touch thereof establishing an electric circuit

to energize a magnet which effects the operation of placing said stop in the off position and a common control device electrically connected to said off magnets, whereby operation of any selected key will effect the changing of all the stops in the on position to the off position.

10 10. A stop action device for organs comprising a plurality of keys associated with an equal number of stops, each stop being operated by its respective key when the latter is initially operated and means common to all stops whereby advanced or double touch of any one of said keys will maintain all of said stops in the off position.

Signed at West Haven, county of New Haven, State of Connecticut, this 4th day of June, 1930.

FREDERICK CAMPKIN.
